UNITED STATES PATENT OFFICE.

ABBOT AUGUSTUS LOW, OF BROOKLYN, NEW YORK.

DESIGN FOR A BOX.

SPECIFICATION forming part of Design No. 23,548, dated August 7, 1894.

Application filed June 9, 1894. Serial No. 514,103. Term of patent 14 years.

To all whom it may concern:

Be it known that I, ABBOT AUGUSTUS LOW, a citizen of the United States, residing in the city of Brooklyn, in the county of Kings and State of New York, have invented and produced a new and useful Design for Boxes, of which the following is a specification, reference being had to the accompanying drawing.

The accompanying drawing represents an isometrical perspective of my design. The leading feature of my design consists in a cylindrical body having end covers the rounded edges of which protrude beyond the periphery of the cylinder and represent annular beadings having milled surfaces.
